UNITED STATES PATENT OFFICE.

HENRY H. WIEGAND, OF BALTIMORE, MARYLAND.

FURNACE-SCREEN.

1,128,206.

Specification of Letters Patent.

Patented Feb. 9, 1915.

Application filed October 21, 1912. Serial No. 726,920.

To all whom it may concern:

Be it known that I, HENRY H. WIEGAND, a citizen of the United States, residing at Baltimore city, State of Maryland, have invented certain new and useful Improvements in Furnace-Screens, of which the following is a specification.

In the operation of boiler furnaces, for example, whenever it is desired to supply fresh fuel to the furnace, or to rake or stir the burning fuel already in the furnace, the stoking door is opened wide. The effect of this is to produce several undesirable results. First, it causes great radiation and loss of heat from the furnace. Second, the intense heat issuing from the furnace through the door opening is very trying on the stoker or fireman, preventing perfect performance of his duties, and in addition thereto intensifies the heat of the boiler room. Third, it results in a great rush of a solid mass of cold air into the furnace, in a large volume, striking among the gases arising from the fire bed, cooling them and causing improper combustion and the production of black smoke. Such a solid mass of cool air also striking the highly heated shell of the boiler causes sudden contractions which produce leaks and damage to the boiler. Moreover, the highly heated brick-work receiving such volumes of cold air is also damaged.

This invention was devised primarily for the purpose of obviating these undesirable results, which follow each time the furnace door is opened, by providing a flexible and penetrable screen or screen door which, while permitting the fire within the furnace to be viewed from the outside and stoked and manipulated with the customary tools, in the ordinary manner, baffles the passage of heat from the furnace through the door opening, and splits such air as enters the furnace through the said opening into many small streams which do not have the ill effects of a large solid mass of cold air rushing into the furnace through the door, as under ordinary circumstances. Moreover, the fireman may work with a great deal more comfort and safety when my improved screen is employed than without.

Though primarily devised for use in connection with boiler furnaces, it will be understood that my invention has also many

other useful applications; as for example, to blast, glass, gas and other furnaces, refrigerating compartments, and compartments containing gases, fumes, or dust, the passage of which it might be desirable to impede through an opening while permitting of the free passage of utensils, or other solid bodies through the opening.

In the following detail description, however, I shall assume that my invention is used in connection with a boiler furnace, and in order to more fully describe my said invention, reference will be had to the accompanying drawings wherein,

Figure 1, represents in front elevation a boiler furnace provided with one form of my improved device; Fig. 2, a fragmentary vertical central section thereof; Fig. 3, a front elevation illustrating a modified form of my invention; Figs. 4 and 5, fragmentary front elevations of boiler furnaces equipped with other specific forms of my invention; and, Figs. 6, 7 and 8, fragmentary detail elevations of several forms in which the yielding members of the screen may be made.

Referring first to the form of my invention shown in Figs. 1 and 2, 1 represents the front of a boiler furnace provided with the usual stoking door opening 2, and hinged door 3, therefor. The door 4, is the door for the ash pit with which we are not concerned in the present description. In this case, my improved screen or auxiliary door comprises, among other parts, a metal bar 5, from which are suspended a plurality of metal chains 6, all lying in close proximity to each other in substantially the same vertical plane, the row of said chains being wide enough to completely cover the furnace door opening; when placed in front of the same, said members being free at their lower ends where they terminate approximately at the bottom of said opening, and are adapted to swing within said opening toward the rear thereof into a substantially horizontal plane when struck from the front. The screen in this case is normally supported by means of a flexible wire cable, or other suitable flexible supporting means 7, attached at one end to a flexible wire cable or other suitable means 8, secured to the bar 5, near each end thereof, the cable 7 passing over pulleys 9 and 10,

and provided at one end with a counter-weight 11.

When the screen is lowered into position in front of the door opening, it is supported by two brackets 12 and 13, which receive the bar 5 near its ends.

When it is desired to stoke the furnace, the ordinary furnace door 3 is opened, and my improved screen is lowered into the position shown in full lines in Fig. 1. In this position of the screen the fireman can readily see the condition of the fire through the screen, can pitch coal through the screen, or insert such implements as may be desired to manipulate the burning fuel in the furnace. At the same time the screen greatly baffles the passage of heat out of the furnace through the door opening, and splits up such air as enters the furnace through the opening, as pointed out in the general introduction to the specification.

When it is desired to close the furnace door 3, the auxiliary door or screen is raised by means of the cable 7, to the dotted line position shown.

In some cases, particularly in marine work, when the screen is supported by means of a cable, as in Fig. 1, it is desirable to provide some means for keeping the screen, as well as the counterweight, from swinging about. One way of doing this is shown in Fig. 3, where I employ guide rods 14 and 15, which extend through openings near the ends of the bar 5; and by providing guide rods 16 and 17, which extend through openings in lugs 18, on the counterweight 11'.

In Fig. 4, I have shown another modification of my invention, in which the support for the chains 6 consists of a lever arm 19, fulcrumed as at 20, and provided, if desired, with a counterweight 21. In this case the screen is placed in front of the door opening of the furnace, or removed therefrom by merely rocking the lever 19 on its fulcrum, causing the screen to travel in a vertical plane.

In Fig. 5, I have shown another modification of my invention in which the screen is movable horizontally to and away from the furnace door opening. In this case the chains 6 are supported from a bar 22, fulcrumed at one end on a vertical rod 23, supported top and bottom in suitable supports 24 and 25, the said bar 22 being braced by a rod 26, secured at one end to the outer end of the bar 22, and at its other end fulcrumed on the rod 23. Thus we have the auxiliary door, or screen, hinged to the front of the furnace on the opposite side of the door opening 2, from the door 3, so that whenever the door 3 is opened, my improved screen may be swung around into position in front of the door opening 2. The opening and closing of the screen in this case may be made automatic by pivotally connecting the

bar 22 of the screen to the ordinary door 3, as by means of a link or connecting bar 27. By this arrangement it will be readily seen that whenever the ordinary door 3 is swung open, this will pull the screen to the closed position, and whenever the screen is swung open, this will pull the door 3 to the closed position. This is merely one of several ways in which the operation of the screen may be made automatic. Other modifications of the construction and mounting of the screen, itself, may also be made without departing from the spirit of my invention.

In Figs. 6, 7 and 8, I have indicated a few of the many forms in which the pendant members may be made when not employing the ordinary chain, as indicated in the foregoing figures.

In the form shown in Fig. 6, each pendant member is made up of a continuous rod or tube 28, and a short length of chain 29, the latter being connected to the bar 5.

In Fig. 7, I have indicated the pendant members as consisting of a series of balls 30, linked together, while in Fig. 8, I have indicated the pendant members as made up of a series of short lengths of tubing 31, joined together by links 32 and 33. These, however, merely represent a few of the large number of different forms which the yielding members of the screen may assume.

Having thus described my invention, what I claim is:

1. A furnace having a stoking opening and a door therefor, in combination with an auxiliary door for said opening adapted and arranged to be brought into operation only when the first mentioned door is opened, said auxiliary door comprising a plurality of flexible non-combustible pendant members with means to support the same, said members being free at their lower ends where they terminate approximately at the bottom of said opening, and adapted to swing within said opening toward the rear thereof into a substantially horizontal plane when struck from the front.

2. The combination with a furnace having a door opening through which the furnace is stoked and the usual door for said opening, of a screen door mounted near said opening so as to be brought in position to cover said opening, or removed from said position, and means to automatically operate the screen door through the movement of the usual furnace door.

3. The combination with a furnace having a door opening through which the furnace is stoked and the usual door for said opening, of a screen door mounted near said opening so as to be brought in position to cover said opening, or removed from said position, the said door being yieldable to the passage of bodies into said furnace therethrough, and means to automatically operate

the screen door through the movement of the usual furnace door, substantially as described.

4. The combination with a furnace having a door opening and the usual door for said opening, of a screen comprising a hinged support and a plurality of chains pendant therefrom in substantially the same plane, and means connecting the said support to the usual furnace door whereby the

opening and closing of the latter door swings said screen toward and away from said opening.

In testimony whereof I affix my signature in presence of two witnesses.

HENRY H. WIEGAND.
